KNOB FOR DOORS, DRAWERS AND THE LIKE

William Doyle Watt, Jr., Grand Rapids, Mich., assignor to
Keeler Brass Company, Grand Rapids, Mich.

Filed Feb. 5, 1962, Ser. No. 68,662

Term of patent 14 years

(Cl. D10—8)

FIG. 1.

FIG. 2.

FIG. 3.

FIG. 4.

FIG. 1 is a perspective view of a knob for doors, drawers and the like embodying my new design.

FIG. 2 is a front elevational view.

FIG. 3 is a side view, and

FIG. 4 is an end elevational view.

I claim:

The ornamental design for a knob for doors, drawers and the like, as shown.
